UNITED STATES PATENT OFFICE

LYDIA B. KOCH, OF NEW YORK, N. Y., ASSIGNOR TO REINFORCED PAPER BOTTLE CORPORATION, OF CHICAGO, ILLINOIS, A CORPORATION OF DELAWARE

PAPER BOTTLE

Application filed February 23, 1928. Serial No. 256,188.

Among the principal objects which the present invention has in view are: to provide a light and strong receptacle of the character mentioned; to provide a nonfracturable receptacle of the character mentioned; to reinforce the structure against being collapsed; to provide additional body reinforcement to the neck of said receptacle; and to provide a reinforced and solid seat for said receptacle.

10 Figure 1 is a vertical section of a milk bottle, constructed and arranged in accordance with the present invention.

Figure 2 is a side elevation thereof.

Figure 3 is a cross section taken on the 15 line 3—3 in Figure 2.

Figure 4 is a bottom view of the cover of said bottle.

Figure 5 is an enlarged sectional view of the neck portion.

20 As seen in the drawings, the receptacle has preferably a cylindrical body portion 8, and a frusto-conical neck portion 9. These are each constructed of sheet paper and of two and more plies thereof. In most cases the 25 two-ply indicated in the drawings and in Figures 1 and 3 thereof, is found sufficient for strength and as offering ample resistance to elements tending to distort or destroy the shape of the receptacle or bottle.

30 The plies indicated in the drawings are constructed from the same piece of material and are wrapped or rolled upon a mandrel, or mandrels. The wrapping or rolling referred to is performed simultaneously for the straight strip from which the body portion 8, is constructed, and from the curved strip of which the neck portion 9, is constructed. These two strips simultaneously produce a reinforced median construction consequent upon 35 the overlapping of the edges of the two strips, as shown in Figure 1 of the drawings. The result of this is that the upper edge of the body portion 8, and the lower edge of the neck portion 9, are reinforced, or made extra 40 pressure resistant.

When rolling the frusto-conical portion 9, an additional strip 10 of narrow material is rolled upon the material at the pouring end of the neck, an added thickness is thereby 45 imparted to this portion of the structure, so

that the end of the material forming the neck may be rolled over upon the added strip 10, and the whole subsequently pressed to form the rounded extended lip 11 and the upwardly opening substantially flat seat 12.

55 When completing the bottle, suitable dies and presses are employed, which forms out of the thickened material the rounded lip 11 of the bottle and the annular seat 12 subsequently employed to receive a bottle cover 60 of approved type.

It will be seen that the neck portion 9 is reinforced at the smaller end by the lip 11, and at the larger end by the four-ply section 13. Also it will be seen that the four-ply section 13 reinforces the upper end or edge of the body portion 8, while the lower edge is reinforced and strengthened by an inserted bottom 14 and the over-curled edge 14' thereof, which forms a strong and solid 70 seating edge.

65 It will be observed by referring to Figure 1 of the drawings that the material forming the edge 14' is completely curled upon itself so that the edges of the body portion 8, and of the flange of the bottom 14 are completely interlocked with the result that the bottom 14 cannot be accidentally forced 75 into the bottle, the overturned edge of the body portion serving to prevent this.

70 The portions 8 and 9 are preferably compressed to harden the same and to insure the mechanical adhesion of the plies forming the structure. In pressing the frusto-conical neck 9 and lip 11, the dies employed are so arranged as to produce the upset ridges 15 which, after being formed assist in reinforcing or preserving the structural unity of the neck of the bottle. It is between two of the ridges 15 that the transparent window 16 is placed. The window 16 is provided to enable the user of the bottle to see the cream-line of the milk contained therein.

80 The sections of the ridges 15 which are formed on the lip 11 reinforce the same and operate as lugs to assist in locking a cap which may be forced down over the lip, with the effect that the said cap is securely held.

85 The recesses 17 formed in the under edge of the pendent flange 11' of the cover 18,

serve to pass over the ridges 15 on the lip 11 without extension of the lip 11 so that after the cover 18 is in position by rotating the cover so that the recesses 17 pass out of alignment with the ridges 15, the cover is locked in service position.

Claims:

1. A paper bottle having a tapered laminated neck portion, a reinforced thickened pouring edge secured thereto, and an added reinforcing filler strip interposed between said neck portion and pouring edge, said thickened portion being molded to form a horizontal upward opening seat, substantially as described.

2. A paper bottle having a tapered laminated neck portion, a reinforced thickened pouring edge secured thereto, an added reinforcing filler strip interposed between said neck portion and pouring edge, said filler strip and associated parts being compressed to a definite form providing an interior seat for a bottle cover, said seat being approximately horizontal and disposed to have free access thereto from above.
